UNITED STATES PATENT OFFICE.

ALBERT T. LIGHT, OF BROOKLYN, NEW YORK.

BATCH-WEIGHING DEVICE.

Application filed November 10, 1923, Serial No. 673,914. Renewed May 6, 1927.

This invention relates generally to automatic batch weighing devices.

The invention includes a charging receptacle mounted to receive material from a source of supply and to automatically shut off the supply of material to the charging receptacle when a predetermined weight of material has been received therein. The invention further includes provision for causing the charging receptacle to automatically tilt to charging position when the predetermined weight of material constituting a charge has been received therein, and for manually locking the receptacle in charging position simultaneously with the opening of a valve permitting the charge to flow into the material-treating device with which the charging receptacle is associated. When the charge has been completely delivered the operator closes the discharge valve and in the same act releases the charge receptacle which thereupon automatically swings back to charge receiving position and in so doing automatically opens the supply valve to permit material to again flow into the charge receptacle from the source of supply.

In the drawings in which a preferred form of the invention has been selected for illustration,

Figure 1 is a view in side elevation of a charge weighing device embodying the invention and showing the device in material receiving position.

Figure 2 is a view similar to Figure 1 and showing the device in material delivering position.

Figure 3 is a view in front elevation of a supply valve with the cover removed.

Figure 4 is a view in vertical section of the valve device shown in Figure 3.

Figure 5 is a view similar to Figure 3 with one of the valve members removed.

Figure 6 is a view in front elevation and partly in section of a discharge valve used in the invention and showing the valve in closed condition.

Figure 7 is a view similar to Figure 6 showing the valve in open position.

Referring to the drawings for a more detailed description of the invention, a charge receiving receptacle is shown at 10 and takes the form of a frusto-conical hollow drum having a considerably greater axial than diametrical dimension and mounted in a horizontal position on a pivoted support or cradle 11 placed nearer to the converging

than the diverging end. With the construction and arrangement described it will be seen that the receptacle tends through its pivotal support to tilt downwardly at its 60 overhung larger end. To offset this and to cause the receptacle to normally take a position tilted in the reverse direction, that is, with the larger end raised, a weight 12 is provided on a post 13 projecting from the 65 smaller end of the receptacle. The weight 12 causes the empty or partially filled receptacle 10 to normally take the position shown in Figure 1 of the drawing.

At 14 is shown a material supply pipe 70 through which material passes from a source, not shown, into the charge receptacle 10 by way of a valve chamber 15. The valve in the chamber 15 is operated by a valve arm 16 which is actuated by engagement with a 75 socket or seat 17 carried by the receptacle, so that when the receptacle is in the position shown in Figure 1 the arm 16 is swung to valve opening position. It will thus be seen that with the receptacle tilted by the 80 action of the weight 12 as in Figure 1 the valve arm 16 is manipulated to permit material to be received in the charge chamber.

When a quantity of material has been received in the charge receptacle sufficient to 85 overbalance the weighted end, the receptacle tilts downwardly at the larger end and takes the position shown in Figure 2 of the drawing. In this position it will be seen that a discharge nozzle 18, with which the receptacle is provided, is lowered into a receiving hopper 19 leading directly into the device or apparatus 20 in which the material is treated.

The discharge nozzle 18 is provided with 95 a valve chamber 21 in which a disk valve 22 cooperates with a discharge port 23. Operating means for the valve 22 include a pinion 24 and a rack 25 carried by a plunger 26 connected at one end to a handle member 27. 100 The handle 27 is adapted to be swung about the pivotal point 28 to open or close the valve 22 and it will be seen that a latch member 29 with which the handle is provided engages with a catch lug 30 formed on 105 the receiving hopper 19 when the valve is in open position as indicated in Figure 7 of the drawings.

It will be seen that with the structural arrangement described when the discharge 110 valve is opened to deliver the contents of the charge receptacle into the treating device

the charge receptacle is locked in the discharging position to insure that the weight 12 will not return the charge receptacle to receiving position before the charge of material contained therein has been completely drained into the material-treating device.

It will also be seen that when the charge receptacle tilts to discharging position the valve arm 16 is moved to the left as in 10 Figure 2, to valve closing position so that material cannot pass from the pipe 14 into the charge receptacle when the receptacle is in receiving position, nor is the receiving valve opened until the handle 27 is moved to 15 unlatching position by the operator. It will be obvious that unlatching the receptacle and permitting it to tilt to charge receiving position under the action of the weight 12 also closes the discharge valve 22 to prepare the 20 receptacle to receive the new charge through the receiving valve.

The receiving valve structure includes a fixed valve plate 31 and a rotatable valve plate 32. Perforations 33 in the rotatable 25 plate cooperate with corresponding perforations 37 in the fixed plate in the position of the valve arm 16 shown in Figure 1. A spring 34 holds the valve 32 to its seat and a set screw 35 is used to hold the cover plate 30 36 of the valve chamber in place. Supplemental openings 38 in the valve plate serve to admit pressure between the valve and its seat and to facilitate the operation of the valve. The arm 16 may be adjusted in angular 35 position on the valve rod and the socket member 17 which receives the end of the arm may also be adjusted to vary the opening or closing movement of the valve arm. It will be clear also that the weight of a charge or 40 batch necessary to tilt the receptacle 10 can be varied by adjustment of the weight 12 on the threaded post 13. The device shown and described may be used, for example, in handling the mixture used in making 45 ice cream.

What I claim is:

1. In a batch weighing device, a receptacle having a pivotal support and adapted to normally assume a certain angular position 50 with relation to the support, a supply valve and means connecting the receptacle and the valve for positively moving the valve to open position when the receptacle occupies said position, said receptacle acting to tilt to discharging position when a predetermined weight of material has been received therein, said connecting means operating to positively move the supply valve to closed position when the receptacle is in discharging position, a discharge valve, and means under control of the operator for locking the receptacle and opening the discharge valve when the receptacle is in discharging position.

2. In a batch weighing device, a receptacle

having a pivotal support and adapted to normally assume a certain angular position with relation to the support, a supply valve and means connecting the receptacle and the valve for positively moving the valve to open position when the receptacle occupies 70 said position, said receptacle acting to tilt to discharging position when a predetermined weight of material has been received therein, said connecting means operating to positively move the supply valve to closed position when the receptacle is in discharging 75 position, a discharge valve, and manually operable means for opening the discharge valve and simultaneously locking the receptacle in discharging position.

3. In a batch weighing device, an elongated receptacle pivotally supported at a point between its center and one end, an adjustable weight carried by said end to cause 80 the receptacle to normally assume a certain angular position with relation to the support, a supply valve and means connecting the receptacle and the supply valve for positively moving the valve to open position when the receptacle occupies said position, said receptacle being arranged to tilt to discharging position when a predetermined weight of material has been received therein, said connecting means operating to positively move the supply valve to closed position when the receptacle is in discharging 85 position, a discharge nozzle carried by the receptacle and adapted to be brought into cooperative relation to a receiving opening in a material treating device when the receptacle is in discharging position, a discharge valve, and manually operable means for opening the discharge valve and simultaneously locking the receptacle in discharging 90 position.

4. In a batch weighing device, a tapering elongated receptacle pivotally supported in a horizontal position between its center and its smaller end, a weight carried by the receptacle at its smaller end to cause the receptacle to normally assume a receiving position with its larger end somewhat elevated, a supply valve and means connecting the receptacle and the supply valve for holding 100 the valve open when the receptacle occupies said position, said receptacle being arranged to tilt to discharging position with the larger end of the receptacle lowered when a predetermined weight of material has been received therein, said connecting means operating to close the supply valve when the receptacle is in discharging position, a discharge nozzle carried by the receptacle and adapted to be brought into cooperative relation to a receiving opening in a material treating device when the receptacle is in discharging position, a discharge valve, and manually operable means 105 for opening the discharge valve and for 110

locking the receptacle in discharging position until manually released.

5. In a batch weighing device, a material treating device, a frusto-conical receptacle 5 pivotally supported thereon in a horizontal position between its center and its smaller end, an adjustably positioned weight carried by the receptacle at its smaller end to cause the receptacle to normally assume 10 a receiving position with its larger end somewhat elevated, a supply valve and means connecting the receptacle and the supply valve for holding the valve open when the receptacle occupies said position, 15 said receptacle being arranged to tilt to discharging position with the larger end of the receptacle lowered when a predetermined weight of material has been received therein, said connecting means operating to close 20 the supply valve when the receptacle is in discharging position, a discharge nozzle carried by the larger end of the receptacle and adapted to be brought into cooperative 25 relation to a receiving opening in said material treating device when the receptacle is in discharging position, a discharge valve, and manually operable means for opening the discharge valve and for locking the receptacle in discharging position until manually 30 released.
6. In a batch weighing device, a receptacle arranged to tilt to discharging position when a predetermined weight of material has been received therein, a supply 35 valve through which material is delivered to the receptacle, means carried by the receptacle for automatically closing the supply valve when the receptacle is tilted to discharging position and for opening the supply valve when the receptacle is tilted to 40 charge receiving position, a discharge valve on the receptacle, means for operating the valve, and means cooperating with the valve operating means for locking the receptacle 45 in discharging position when the discharge valve is open.

7. A batch weighing device comprising a receptacle adapted to move from a charge re-

ceiving position to a discharge position upon receiving a predetermined weight of material, a disc valve controlling the discharge from the receptacle, manual means for operating the discharge valve, and means cooperating with the valve operating means for positively locking the receptacle in discharge position during opening movement of the valve operating means.

8. A batch weighing device comprising a receptacle adapted to move from a charge receiving position to a discharge position upon receiving a predetermined weight of material, a supply line for delivering material to said receptacle, a valve in the supply line, and means controlled by movement of the receptacle for positively moving the valve to open position during movement of the receptacle to charge receiving position, said means operating to positively move the valve to closed position during movement of the receptacle to discharge 70 position.

9. A batch weighing device comprising a receptacle adapted to move from a charge receiving position to a discharge position upon receiving a predetermined weight of material, a supply line for delivering material to said receptacle, a disc valve in the supply line, and means controlled by movement of the receptacle for positively moving the valve both to open and closed 80 positions.

10. A batch weighing device comprising a receptacle adapted to move from a charge receiving position to a discharge position upon receiving a predetermined weight of material, a supply line for delivering material to said receptacle, a disc valve in the supply line, a seat on which the disc valve operates, means for admitting pressure between the disc valve and its seat, and means controlled by movement of the receptacle for positively moving the valve both to open 85 and closed positions.

In testimony whereof I affix my signature.

ALBERT T. LIGHT.
